UNITED STATES PATENT OFFICE.

HERMAN IHLENBURG, OF PHILADELPHIA, PENNSYLVANIA, ASSIGNOR TO MACKELLAR, SMITHS & JORDAN, OF SAME PLACE.

DESIGN FOR PRINTING-TYPES.

Specification forming part of Design No. 7,783, dated September 29, 1874; application filed September 23, 1874.
[Term of Patent 14 years.]

To all whom it may concern:

Be it known that I, HERMAN IHLENBURG, (assignor to MACKELLAR, SMITHS & JORDAN,) of the city and county of Philadelphia, Pennsylvania, have invented and originated a new and original Design for Printing-Types, of which the following is a specification:

The nature of my design is fully illustrated in the accompanying typographic specimen, to which is reference is made; and consists of a black letter, shaded and ornamented as shown.

What I claim as new is—

The design for a font of printing-type, as shown.

HERMAN IHLENBURG.

In presence of—

C. F. HUCH,

JAMES G. BERKHEIMER.
